UNITED STATES PATENT OFFICE.

WILHELM A. LUUKKONEN, OF BROOKLYN, NEW YORK.

ATTACHMENT FOR MOTOR EXHAUSTS.

Application filed September 13, 1927. Serial No. 219,360.

This invention relates to attachments for motor exhausts, the primary object of the invention being to provide an attachment which is in the nature of a sounding device 5 to be connected to the exhaust pipes of an internal combustion engine so that the gases escaping from the exhaust pipes will cause the device to sound and even an ordinary layman can tell by the sound whether or 10 not the engine is operating properly, and also to determine to a great extent just what is wrong with the engine.

A further object is to provide a device of this character which can be manufactured 15 and sold at an extremely low price, which will be strong and durable in use, and which will most efficiently perform the functions for which it is intended.

With these and other objects in view, the 20 invention consists in certain novel features of construction and combinations and arrangements of parts which will be more fully hereinafter described and pointed out in the claims.

25 In the accompanying drawings—

Figure 1 is a view in side elevation, showing my improved device attached to the end of an exhaust pipe;

Figure 2 is an end elevation of Figure 1;

30 Figure 3 is a broken top plan view of Figure 1;

Figure 4 is a view of the vibrator detached;

Figure 5 is a broken view of the blank 35 which is bent to form the support for the vibrator.

1 represents the exhaust pipe of an internal combustion engine. On this pipe I secure my improved device which includes a 40 clamp 2 having an arm 3 thereon that extends downwardly from the lower portion of the clamp and then upwardly and rearwardly, forming a supporting bar 4.

To this supporting bar 4 I connect my 45 improved vibrator 5, which may be of any desired size and shape, and of metal or any other suitable material. This vibrator is normally spaced from the supporting bar 4 and has a depending integral tongue 6 which 50 is secured to the bar 4 by rivets 7 or other suitable attaching means.

The vibrator is free to bend along the tongue 6 and may move toward and away 55 from the supporting bar as indicated by the dotted line positions in Figure 1. The ex-

haust from the engine blowing against the vibrator causes the latter to vibrate and make a sound, and the ear of the experienced operator can detect by the sound defects in the operation of the motor.

I have illustrated a particular construction which shows the clamp 2 with the arm 3 and bar 4, all constituting a single integral sheet metal blank which is bent into the desired shape. The parts 3 and 4 are 60 disposed at right angles to the part 2, and said part 2 is bent so as to fit around the exhaust pipe and has perforations 8 in its ends to receive a screw 9 and wing nut 10 to clamp the same around the exhaust pipe. 65

It is perfectly obvious that the device may be made in various ways and include any desired number of parts but in any event I employ a supporting member connected to the exhaust pipe, and a vibrator 70 connected to the support and mounted so as to freely vibrate or create a sound or noise due to the gases.

It is to be understood of course that the 75 particular sound will depend upon the operation of the engine. In other words, if the engine is operating perfectly, the vibrator will make regular sounds, and, if the engine is operating imperfectly, it will make irregular sounds, and the differences 80 in the sounds will give the operator knowledge as to the working of the engine.

To prevent any possibility of the vibrator being drawn by suction against the end of the exhaust pipe, I extend the clamp beyond 85 the end of the exhaust pipe and provide openings 11 in the projecting portion of the clamp.

While I have illustrated what I believe to be a preferred embodiment of my invention, 90 it is obvious that various changes and alterations might be made in the general form of the parts described without departing from the invention and hence I do not limit myself to the precise details set forth but consider myself at liberty to make such changes and alterations as fairly fall within the 95 spirit and scope of the appended claims.

I claim:

1. A device of the character described, including a clamp adapted to be positioned on the exhaust pipe of an internal combustion engine and project beyond the end of the pipe, said clamp having an opening in its 100 projecting portion, and a vibrator opera- 105

110

tively connected to the clamp and located in the path of the exhaust gases from the exhaust pipe.

2. A device of the character described, including means for attachment to an exhaust pipe of an internal combustion engine, a depending arm on said means, an upwardly projecting bar integral with the arm, and a vibrator secured to the bar but movable relative thereto and said vibrator located in the path of the exhaust gases.

3. A device of the character described, including means for attachment to an exhaust pipe of an internal combustion engine, a depending arm on said means, an upwardly projecting bar integral with the arm, a vi-

brator, and a tongue on the vibrator fixed to the bar and resiliently bendable so as to permit the vibrator to move toward and away from the bar and said vibrator located in 20 the path of the exhaust gases.

4. As an article of manufacture, a device adapted to be connected to the exhaust of an internal combustion engine and a vibrator connected to the device and caused to sound 25 by the escape of gases from the exhaust and said vibrator located in the path of the exhaust gases.

Signed at city of New York, in the county of New York, and State of New York, this 30 12th day of September, A. D. 1927.

WILHELM A. LUUKKONEN.
